UNITED STATES PATENT OFFICE.

JOHN O. HOUSER, OF PITTSBURG, PENNSYLVANIA.

DIE FOR FORMING TWIST-DRILLS.

SPECIFICATION forming part of Letters Patent No. 651,356, dated June 12, 1900.

Application filed March 18, 1899. Serial No. 709,570. (No model.)

To all whom it may concern:

Be it known that I, JOHN O. HOUSER, a citizen of the United States, residing at Pittsburgh, in the county of Allegheny and State of Pennsylvania, have invented or discovered a new and useful Improvement in Dies for Forming Twist-Drills, of which the following is a full, clear, and exact description, reference being had to the accompanying drawings, forming part of this specification, in which—

Figure 1 is a face view of the die used in forming my improved drill. Fig. 2 is a horizontal section through the die, taken on the line II II of Fig. 1. Fig. 3 shows a vertical section of the die and a blank being drawn therethrough in the operation of forming the spiral groove. Fig. 4 is a face view of the finishing-die. Fig. 5 is a view of a finished twist-drill sharpened at both ends.

My invention relates to the art of forming twist-drills by drawing a blank through forming-dies; and it consists in the improved die therefor.

Referring now to the drawings, 2 is the die, of hardened steel, provided with an opening 3, through which the blank 4 is drawn by any suitable mechanism and in which it is formed. This opening is generally circular in form, corresponding to the diameter of the finished drill, and at opposite sides are the inwardly-extending groove-forming projections 5, angularly arranged across the inner faces of the opening 3, tapering from the point of contact with the blank inwardly, and terminating in curved finishing edges, so as to form in the blank the opposite spiral grooves 6 as the blank is drawn through the die. Spiral movement will be imparted to the blank in its passage by reason of the angular location of the projections, and the gripping and drawing mechanisms may be made to have a corresponding rotary movement when moving forwardly, or a rotating die may be used with a non-rotating blank with equally good results.

The die shown in Fig. 2 and, if desired, any subsequent dies in the operation before finishing are designed to accomplish but a partial reduction of the blank, while the fin-

ishing-die (shown in Fig. 4) is designed to enlarge the grooves to the finished size and to reduce the intervening metal to a proper thickness.

It will be understood that the continuously-spiral finished blank may be made in any desired length, after which it may be cut into suitable sizes for work and then it is sharpened at each end to cutting-faces 7, when it is ready for use.

The advantage of a twist-drill having a continuous spiral, and thus permitting a cutting-face to be provided at each end, will be appreciated, since such a drill may be used reversibly in the drill-chuck, allowing it to be used just twice as long as the ordinary drill without regrinding. The manufacture of such drills is rendered possible by my improved die, their cost is greatly reduced, the uniformity of the drill is insured, and the density of the metal greatly increased, and these advantages contribute largely to the economical production of this class of drills as an article of manufacture and will be appreciated by those skilled in the art.

What I claim is—

1. A die for forming twist-drills from cylindrical blanks having an opening through which the blank is drawn, in which oppositely-disposed inner edges of the die conform to the diameter of the finished drill, and intermediate inwardly-extending projections conform to and produce the grooves of the drill by compression in the passage of the blank through the die.

2. A die for forming twist-drills from cylindrical blanks provided with a circular opening corresponding to the diameter of the blank and oppositely-disposed angularly-arranged groove-forming projections tapering from the point of contact with the blank inwardly and terminating in curved finishing edges.

In testimony whereof I have hereunto set my hand.

JOHN O. HOUSER.
